Primary Examiner—Prabhakar G. Deshmukh

[57] **CLAIM**

The ornamental design for a “helicopter video game collective pitch controller”, as shown.

DESCRIPTION

FIG. 1 is a perspective view of a helicopter video game collective pitch controller showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing of an electrical conduit is for illustrative purpose and forms no part of the claim.
